RETRACTABLE UNDERCARRIAGE FOR
AIRPLANES

Pierre Martin Joseph Lallemand, Port-Marly, France, assignor to Société Hispano-Suiza-Lallemand, Bois-Colombes, France, a society of France

Filed Feb. 19, 1962, Ser. No. 173,953

Claims priority, application France Aug. 8, 1961
3 Claims. (Cl. 244—102)

The present invention relates to undercarriages for airplanes, comprising struts to be retracted individually into the airframe of the airplane, for instance into the fuselage or into nacelles incorporated in the wings of the airplane. The invention is more especially but not exclusively concerned with airplanes of the high wing type, where the struts of the main landing gear are to be retracted into nacelles incorporated in the high wing of the airplane.

The chief object of this invention is to provide an undercarriage of the above mentioned type which is better adapted to meet the requirements of practice than those known up to this time, in particular concerning the space that is occupied in retracted position.

This invention relates to the case where the undercarriage comprises at least one strut including a shock-absorber pivoted at its lower end to the support of the wheel belonging to said strut and at its upper end to a rigid connecting member disposed substantially in vertical alignment with said shock-absorber and itself pivoted to the airframe of the airplane and the invention is characterized in that retraction of said strut is obtained by means of at least one telescopic fluid actuator the ends of which are pivoted respectively to the airframe of the airplane and to said rigid connecting element.

A preferred embodiment of this invention will be hereafter described with reference to the appended drawings, given merely by way of example, and in which:

FIG. 1 is a side view of an undercarriage according to the invention, shown in the down position;

FIG. 2 is a similar view showing the undercarriage in partly retracted position;

FIG. 3 is a similar view showing the undercarriage in wholly retracted position.

In the embodiment of the invention illustrated by the drawings an undercarriage is intended to be retracted into a nacelle 1 incorporated in one of the half-wings of the airplane.

The main strut of the undercarriage comprises a shock-absorber 2, preferably an oleo-pneumatic shock-absorber of the telescopic type, the lower end of which is pivoted at A to the support 5 of wheel (of pair of wheels) 3 corresponding to this strut and the upper end of which is pivoted at B to a rigid connecting element 4 extending substantially in line with said shock-absorber 2 when the undercarriage is in the down position, this element 4 being itself pivoted at C to the airframe of the airplane. Preferably pivot points A, B and C are at least approximately located on a vertical line when the undercarriage is in the down position.

In the embodiment of the invention illustrated by the drawings, interconnecting element 4 is in the form of a piece having a general triangular outline.

Wheel support 5 is preferably arranged, as shown, so that the undercarriage is of the so-called "indirect" type, said support consisting, as shown, of a lever 5 at one end of which wheel 3 is journaled. To the other end of lever 5 there is pivoted, at B, a rod 6 the upper end of which is pivoted at E to the airframe of the airplane. Said rod 6 is connected to element 4 through a rigid link 7 one end of which is pivoted at F to an intermediate

2

point of rod 6 and the other end of which is pivoted to element 4 at a point G. Preferably, as shown by the drawings, this point G is located, with respect to line A, B, C, on the side thereof opposed to that toward which wheel 3 is to be lifted. The point A where shock-absorber 2 is pivoted to the wheel supporting lever 5 is located between the ends of said lever 5.

Now, according to the main feature of this invention, retraction of the undercarriage is effected by means of 10 at least one fluid actuator, preferably a hydraulic one, one of the ends of which is pivoted to the airframe and the other end of which is pivoted to connecting element 4, this actuator 8, which is preferably of the double acting type, being arranged in such manner that, during the 15 retraction operation, it causes connecting element 4, to pivot about point C in a direction such that this movement produces an upward retraction of the deformable system A, B, C, D, E, F.

Preferably, in order to reduce as much as possible the 20 space occupied by the undercarriage in retracted position, actuator 8 is mounted so as to exert a pulling thrust during the retraction of the undercarriage. For this purpose said actuator must be located, with respect to line A, B, C, on the side thereof opposed to that toward 25 which wheel 3 must be moved upwardly. Actuator 8 is pivoted at one end, at H, to the airframe and at I to connecting element 4.

When comparing FIG. 2 (partly retracted position) and FIG. 3 (wholly retracted position) with FIG. 1 the 30 following points should be noted:

(a) retraction of the undercarriage is accompanied by a substantial reduction of its length so that the space necessary for housing the retracted undercarriage is reduced with respect to the relatively great height of this 35 undercarriage in the down position, made necessary by the fact that the wing is a high wing;

(b) the whole of the lifting mechanism is constantly located in a reduced space extending approximately 40 above the corresponding wheel, which has but a small displacement in the longitudinal direction of the airplane during the retraction operation; and

(c) actuator 8, due to the substantial alignment of 45 points A, B, C withstands practically but a small portion of the efforts applied to the wheel when the aircraft is taxiing on the ground.

Of course the undercarriage above described may be fitted with all suitable safety devices, such for instance as a device for locking the undercarriage in the down 50 position (acting for instance upon the actuator), an electric signalling device operated by the locking device and indicating to the pilot that the undercarriage is truly in down position for landing, a device for cutting off the feed of liquid to the actuator when the undercarriage is in the down position and so on.

Of course the invention is not limited to the particular embodiment thereof shown by the drawings.

What I claim is:

1. For use with an airplane fixed structure, an undercarriage unit which comprises, in combination, a rigid member pivoted to said airplane structure about a single first axis transverse to the fore-and-aft direction of the airplane, a wheel, a rigid wheel support, a shock absorbing strut pivoted at one end to said rigid member about a single second axis and at the other end to said wheel support about a single third axis, respectively, both of said second and third axes being transverse to the fore-and-aft direction of the airplane, said strut extending along a line intersecting said first and second axes transversely thereto when the undercarriage unit is in the down position, a hydraulic actuator for retracting said strut, said actuator including two elements telescopically

movable with respect to each other, one of said elements being pivoted to said airplane structure and the other of said elements being pivoted to said rigid member about a fourth single axis and a fifth single axis, respectively, both transverse to the fore-and-aft direction of the airplane, said wheel support being a lever pivotable about said third axis, said wheel being journalled in said lever at one end thereof, a rod pivoted at one end to the said lever and at the other end directly to said airplane structure about respective axes transverse to the fore-and-aft direction of the airplane, and a rigid link pivoted at one end to an intermediate point of said rod and at the other end to said rigid member about respective axes transverse to the fore-and-aft direction of the airplane.

2. For use with an airplane fixed structure, an undercarriage unit which comprises, in combination, a rigid member pivoted to said airplane structure about a single first axis transverse to the fore-and-aft direction of the airplane, a wheel, a rigid wheel support, a shock-absorbing strut pivoted at one end to said rigid member about a single second axis and at the other end to said wheel support about a single third axis, respectively, both of said second and third axes being transverse to the fore-and-aft direction of the airplane, said strut extending along a line intersecting said first and second axes transversely thereto when the undercarriage unit is in the down position, a hydraulic actuator for retracting said strut, said actuator including two elements telescopically

movable with respect to each other, one of said elements being pivoted to said airplane structure and the other of said elements being pivoted to said rigid member about a single fourth axis and a single fifth axis, respectively, both transverse to the fore-and-aft direction of the airplane, said wheel support being a lever extending on opposite sides of said third axis, said wheel being journalled in said lever at one end thereof, a rod pivoted at one end to the other end of said lever and at the other end directly to said airplane structure about respective axes transverse to the fore-and-aft direction of the airplane, and a rigid link pivoted at one end to an intermediate point of said rod and at the other end to said rigid member about respective axes transverse to the fore-and-aft direction of the airplane, said first, second and third axes being located in a common vertical plane transverse to the fore-and-aft direction of the airplane when the undercarriage is in the down position.

3. An undercarriage according to claim 2 wherein said hydraulic actuator is located, with respect to the common plane of the first, second and third axes, on the side thereof opposed to that toward which said wheel is moved upwardly when the undercarriage is retracted.
